ELECTRICALLY WOUND CLOCK

Victor James Samuel Russell and Eric Beecroft
 Moss, Cricklewood, England, assignors to S.
 Smith & Sons (Motor Accessories) Limited,
 Cricklewood, London, England, a British company

Application August 28, 1942, Serial No. 456,552
 In Great Britain June 30, 1941

5 Claims. (Cl. 58—41)

This invention relates to electrically wound clocks of the kind in which the clockwork mechanism as it runs down closes a switch and completes an electric circuit to energise an electromagnet, which magnet operates an armature arranged to re-stress the winding spring and to interrupt the electric circuit. In such clocks, where the armature moves with the unwinding of the clock the circuit is usually completed by a snap-action switch, which is closed by the armature at one limit of its movement. This type of switch has been employed because the switch requires to be maintained in its closed position during the movement of the armature under the control of the electromagnet, since the armature then ceases to apply a closing force to the switch.

According to the present invention an electrically wound clock of the kind first referred to above is characterised in that a switch for controlling the energisation of the electromagnet is biased towards an open position and after being closed by means operated by the running down of the clockwork mechanism and thereby energising the electromagnet, is maintained closed by flux from the electromagnet during the resulting movement of the armature, which re-stresses the winding spring. For example, a moving part of the switch may have associated therewith a second armature arranged in the flux path of the magnet so that when the magnet is energised the second armature is moved in opposition to the aforesaid bias.

In one form of construction according to this invention two switches are arranged in series in the electromagnet circuit, which are respectively arranged to be operated by the first said armature at opposite ends of its movement, one of which switches is biased towards the open position and is provided with said second armature, and the other of which is biased towards a closed position, the latter being arranged to be opened when the armature has completed its movement under the influence of the magnet, while the other switch is arranged to be closed when the armature is in a position corresponding to the run-down condition of the clock.

Each of said switches may be of the kind comprising a pair of contacts at least one of which is mounted on a resilient or pivoted arm.

The movement of the first said switch into the closed position may be by a mechanical connection between the armature or part moving therewith. In order to prevent the electromagnet winding from being overheated or burnt out in the event of the contacts remaining perma-

nently closed, a thermostat device is arranged to be influenced by heat generated in the electric circuit, and is arranged to open one or the other of the switches when excessive heat is generated. For example, the thermostatic device may comprise a bi-metallic strip which constitutes a flexible support for one of the contacts, and is encircled by a heating coil in circuit with the electromagnet.

- 10 The following is a description of two alternative forms of construction, reference being made to the accompanying drawing in which both Figures 1 and 2 are perspective views of the mechanism.
- 15 In the construction shown in Figure 1, the usual form of rotary armature 10 is pivoted about the mid point of the electromagnet coil 11 and is provided with curved end pieces 12 which are arranged to sweep over the ends of the core 13 of the electromagnet. The electromagnet circuit has two pairs of contacts 14, 15 and 16, 17 respectively, arranged in series, the first said pair being biased to open and the other being biased to close. The moving contact arm 18 which carries the contact 14 of the biased open pair of contacts comprises a resilient blade which is anchored at one end to an insulating block 20 mounted on a fixed part of the device. The arm has secured to its other end a small block of magnetic material 19 which is disposed at one end of the coil in the flux path between one of the poles 13 and an extension plate 23 secured to the other pole. The other contact 15 is arranged between the arm 18 and the coil and is carried by a resilient blade 21 secured at one end to a fixed block 22. With this arrangement, the flux from the magnet tends to move the block of magnetic material and draws the contact 14 into engagement with the contact 15. In the attracted position of the said block 19 a small air gap is left between it and said extension 23 and adjacent pole-piece 13 so that when the magnet is de-energised the contact 14 may be retracted by a light biasing spring 24 connected between the arm 18 and an anchorage member 25. The main armature 10 rotates with the unwinding of the clock and is provided with an extension piece 26 shaped to engage the end of the arm 18 when the clock is nearly unwound so as to move the contact 14 into engagement with the contact 15 against the bias of the spring 24. The main rotary armature is also provided with a second extension piece 27 arranged to engage an arm 28 on which the contact 16 of the second pair of contacts is mounted, the other end of said arm

being secured to an insulating block 29. The engagement of the second extension piece 27 with the arm 28 is arranged to take place when the main armature is reaching the end of its travel under the influence of the electromagnet.

In operation, when the electromagnet is de-energised, the main armature 10 is moved with the unwinding clock spring 30 until the first extension piece 26 closes the aforesaid contacts 14, 15. The electromagnet is thus energised and the small block of magnetic material 19 is attracted thereby ensuring that the contacts remain closed when the first extension piece and armature reverse their movement under the influence of the electromagnet. The main armature in being attracted by the electromagnet, stores up energy in a winding spring 31 which when the electromagnet is again de-energised drives the clock through the ratchet mechanism 35 and the shaft 32, at the same time stressing the maintaining spring 30 which keeps the clock running while the main spring is being re-stressed. Towards the end of the movement of the armature under the influence of the electromagnet, the second extension piece 27 opens the biassed closed contacts 16, 17 and interrupts the circuit. The biassed open contacts are thus allowed to open and the main armature moves in the reverse direction under the influence of the spring 31 as indicated above.

It will be seen that the premature opening of the contacts 14 and 15 cannot occur as they are held closed by the flux between the extension plate 23 and one of the pole-pieces 13. Furthermore, the contacts 16 and 17, which interrupt the circuit are only opened when the main armature has acquired an appreciable amount of kinetic energy, so that rapid opening is effected.

The arm 28 which carries the contacts 16 may be in the form of a bi-metallic strip which is encircled by a heating coil 33 in circuit with the electromagnet.

It will thus be seen that if the main armature fails to move sufficiently to open these latter contacts, due for example, to a fall in supply voltage, then the contacts will eventually open due to the heating of the bi-metallic strip and interrupt the circuit.

The construction shown in Figure 2 differs from that described above in the means whereby the rotating armature closes the contacts 14 and 15 when the clock is run down. In this instance, instead of the lower end of the armature being provided with the upward extension 26, the upper end of the armature is provided with a contact-making pin 33 which is arranged to be brought into engagement with a contact plate 34 secured to the arm 18 to which the contact 14 is secured. Thus, as in the previous construction, at the extremity of the movement of the armature 10 during the running down of the clock, the two contacts 14 and 15 are brought together, energising the electromagnet coil 11 which then maintains the contact 14 in engagement with the contact 15 under the action of the block 19 of magnetic material. The armature is then moved under the action of the electromagnet until the extension piece engages the arm 28 and opens the contacts 16 and 17 and breaks the circuit.

We claim:

1. An electrically wound clock comprising a spring-energised clockwork mechanism, a switch, means for biasing the switch towards an open position, means operated by the running down

of the clockwork mechanism to close said switch, an electromagnet energised by the closing of said switch, an armature adapted to be moved by the electromagnet so as to restress the spring

5 of the clockwork mechanism and means influenced by the electromagnet to maintain the switch closed during the resulting movement of said armature to restress said spring, a second switch in series with said first switch, means for 10 biasing said second switch to closed position, and means operable by said armature toward the end of the spring restressing movement to open said second switch.

2. An electrically wound clock comprising a 15 spring-energised clockwork mechanism, a switch, means for biasing the switch towards an open position, means operated by the running down of the clockwork mechanism to close said switch, an electromagnet energised by the closing of said 20 switch, an armature adapted to be moved by the electromagnet so as to restress the spring of the clockwork mechanism, and a second armature influenced by the electromagnet and adapted to maintain the switch closed during 25 the movement of the first armature in restressing said spring, a second switch in series with said first switch, means for biasing said second switch to closed position, and means operable by said armature toward the end of the spring restressing movement to open said second switch.

3. An electrically wound clock comprising a 30 spring-energised clockwork mechanism, an electromagnet, two switches in series with said electromagnet and a source of electric supply, an armature adapted to be moved by the electromagnet to re-energise the spring of the clockwork mechanism, means for biasing one of said switches towards an open position, a second armature associated with that switch and adapted to be influenced by said electromagnet so as to maintain that switch closed during the movement of the first said armature in restressing the clock spring, means biasing the other switch to a closed position, means operated by the first 40 said armature so as to open that switch when the armature has completed its restressing movement under the influence of the magnet, and means operated by the running down of the 45 clockwork mechanism to close the first said switch.

4. An electrically wound clock comprising a 50 spring-energised clockwork mechanism, a switch, means for biasing the switch towards an open position, means operated by the running down of the clockwork mechanism to close said switch, an electromagnet energised by the closing of said 55 switch, an armature adapted to be moved by the electromagnet so as to restress the spring of the clockwork mechanism, means influenced by the electromagnet to maintain the switch closed during the resulting movement of said armature, and a thermostatically controlled switch adapted to be influenced by heat generated in the electric circuit, and adapted to open the 60 energising circuit when excessive heat is developed, said second switch being normally biased to closed position, and means operable by said armature toward the end of the spring restressing movement to open said second switch.

70 5. An electrically wound clock comprising a spring-energised clockwork mechanism, a switch, means for biasing the switch towards an open position, means operated by the running down of the clockwork mechanism to close said switch, 75 an electromagnet energised by the closing of

said switch, an armature adapted to be moved by the electromagnet so as to restress the spring of the clockwork mechanism, a second armature associated with said switch and adapted to be influenced by the electromagnet so as to maintain the switch closed during the movement of the first said armature in restressing the clock spring, a second switch in series with said first switch, means normally closing said second switch, a resilient bimetallic strip adapted to 10 carry a contact of said second switch, a coil surrounding the bimetallic strip and in circuit

with the electromagnet, which bimetallic strip is adapted to open the said second switch when current flows through said coil and electromagnet for a period of time substantially in excess of that required to move said first armature to a position in which the spring is restressed, and means operable by said armature toward the end of the spring restressing movement to open said second switch.
